FOUNTAIN PEN

Lloyd A. Brooke, Washington, D. C.

Application December 18, 1942, Serial No. 469,484

13. Claims. (Cl. 120—47)

My invention is in that class of fountain pens which contain within themselves the means whereby the ink barrel may be filled, and which are usually termed "self-filling" fountain pens. The preferred type of such pens is that wherein the cap of the pen, which is usually employed to cover and protect the pen point itself, is used on the other end of the barrel as an exterior piston by means of which any unused ink, as well as any sediment that may have been deposited, is first forced out of the barrel, and then by a single pull or "draw" of the piston the barrel is filled to the intended extent with a new supply of ink. Thus, inasmuch as the volume of ink always equals the volume of ink, sediment, and air displaced by the thrust of the piston, the piston becomes in fact a measuring device with which the pen may be filled. The amount of ink taken into the pen by any one filling operation is always the same.

The objects of the invention are to produce a pen having a large ink capacity; one that shall not use any rubber sack, sleeve or the equivalent; and a pen that shall always be filled with the proper amount of ink, and by a single operation of the piston.

Another object of the invention is to produce a pen of simple construction; and yet have a large ink capacity, a minimum number of parts, and one that is inexpensive to build and maintain.

A still further object is to produce a pen which has a special valve construction; whereby a ready movement of air into and out of the barrel during the filling operation is possible, but which shall prevent the passage of ink or air at all other times.

With these and other objects in view, reference is made to the accompanying drawings forming a part of this specification for a full understanding of the invention.

Fig. 1 is a sectional elevation of the pen filled and closed.

Fig. 2 is a sectional elevation of the structure showing the pen cap in use as a piston partially withdrawn, as in the filling operation.

Fig. 3 is a partial sectional elevation of the rear end or top of the pen, showing a check valve, and a cage therefor, with the filling cap as piston forced down, as during the filling operation.

Fig. 4 is an enlarged end view of the filling piston and cover cap on line 4—4; Figure 3.

Fig. 5 is a partial sectional elevation of the rear end of the pen closed, using a modified check valve, including a stem on which a spring is mounted.

Fig. 6 is a sectional elevation of a modified construction, the pen being filled and closed; the pen cap being of a somewhat different form from that shown in Figs. 1, 2 and 3.

Fig. 7 is a sectional elevation of the structure of Figure 6; showing the filling cap separated from its head, and withdrawn as during the filling operation.

Fig. 8 is an enlarged end view of the filling cap of Figures 6 and 7 on line 8—8, Figure 7.

Fig. 9 is an enlarged end view of the cap collar of Figures 6 and 7 on line 9—9, Figure 7.

Fig. 10 is an enlarged sectional elevation of the open end of the filling cap and collar, showing a further modification of the parts.

Fig. 11 is an enlarged end view of the filling cap of Figures 6 and 7 at line 11—11, Figure 10, with collar removed.

Fig. 12 is a sectional elevation of the pen filled and closed, showing a structure which is a still further modification.

Fig. 13 is a sectional elevation of Figure 12, showing the filling cap partially withdrawn, as during the filling operation.

Fig. 14 is a partial sectional elevation of the rear end of Figure 12, showing the check valve raised, and about to be thrust down by the piston, as during the filling operation.

Fig. 15 is an enlarged view, on line 15—15, Figure 14.

Several forms of the invention are shown. These will be described one after the other, beginning with the form shown on sheet 1.

The same reference numerals indicate corresponding parts throughout the several views.

The drawings disclose three separate and distinct forms of the invention; the first, that shown in Figs. 1—4; second, that illustrated by Figs. 6 to 9, inclusive; third, the forms disclosed by Figs. 12 to 15, inclusive. These will be described in the order given, but many of the parts of the second and third forms are identical with those of the first form, so that it will not be necessary to describe the second and third forms as the detail is the same as the first form.

Figs. 1, 2, 3 and 4

Referring to Figures 1, 2, 3, and 4, the barrel 1, the cap 2, the connection 3, the feed plug 4, the pen point (nib) 5, and the rear cap 6 are of the usual type in external appearance. The barrel 1, preferably is of translucent plastic material. It is externally threaded, in the usual manner, to receive the cap 2, which also is preferably of the same material. This barrel 1 forms

the ink chamber, and has the plug 4 and pen 5 at the one end, here termed the lower end, and is substantially closed at the other end, here termed the upper end, but which is provided with an opening 8 thereon, for purposes to be described. The connection 3, also preferably of plastic material, may be integral with the barrel 1, or made as a separate piece, as desired. The barrel terminates in an approximately flat end at 7, in which is the comparatively small orifice 8. While this opening is relatively small, it is sufficiently large as not to throttle the incoming or outgoing air during the filling operation.

The opening 8 terminates at its outer end in a valve seat 9, which is to receive a ball check valve 10, of hard rubber, plastic, or similar suitable material.

The upper end of the barrel 1 is fitted with an internal thread, to receive a sleeve or housing 11, also of some suitable plastic or other proper material. And within this sleeve or housing 11, is a cage 12, containing the valve 10 itself. The barrel is internally threaded at this end, and the thread extends to a shoulder, which is recessed to a smaller diameter at 13 down to the level of the check valve seat 9. The outer edge of this end of the barrel is slightly beveled at 14, to provide for its easy entrance into the filling cap 2, when the latter is used as a piston with which to fill the barrel.

The housing 11 is externally threaded for its entire length, and the end which is screwed into the barrel is cemented in place, or otherwise suitably secured in position, when the pen is assembled. Within the housing 11 is a chamber, within which the check valve 10 is placed, but loosely enough for the valve to move up and down a small distance; for instance, an eighth of an inch, more or less, so that it may rest on the valve seat 9 when down, or on a conical top 15 of the chamber when lifted, as when the piston is drawing ink into the barrel, and the enclosed air must escape. In assembling the structure, the unit formed by the valve 10, the housing 11, and the cage 12, are together placed in the barrel, and the housing screwed down until it rests on the shoulder, and is then cemented, or otherwise secured in position. The housing 11 is somewhat longer than the threaded opening in which it is placed, and therefore extends above the same, and the parts are so proportioned that the rear cap 6, which closes the top, can be screwed on to this extension.

The cage 12, preferably made of metal, is substantially a hollow cylinder having at the inner end a recess to contain the ball check 10. This recess has a diameter sufficient to allow the ball check free motion, and is of a length to permit the ball 10 to move upward sufficiently to permit the free passage of air during the filling operation (Figure 2).

This recess is slightly closed at 16 (Fig. 2) after assembling the valve in the cage, as at 16 (Fig. 2) just sufficiently to retain and hold the ball 10. The upper end of this cage terminates in a shoulder 17 of such form as to prevent the sticking of the ball 10. The cage is further fitted with slots 18, cut through to the outside of the cage, and extending from the bottom to a point above the shoulder 17. These slots 18, and the clearance between the ball valve and the inside diameter of the chamber, allow a free flow of air to by-pass the valve at all times during the filling operation. From the shoulder 17 in the

cage 12, a circular hole extends to the outer end of the cage. This allows a free flow of air therethrough, as well as performs another function which will be described below. On the outer end of the ball check cage 12, there is arranged a small button-like head 19, of such shape as to leave free the opening through the cage. The outer flange of this head 19 is slightly flared, to make it easy to take hold of with the fingers and lift. This flange is secured in position in any approved manner, after assembling the valve 10 and cage 12 in the housing 11. The outside of the cage should be made to fit snugly but freely in the recess of the housing 11, both at the cylindrical and conical sections of the recess, so that the friction is sufficient to hold it in raised position (Figure 3). In the down or lowered position, the cage 12 should come to rest on the flange of the button-like head 19, and not on the bottom of the recess, so that the valve 10 can rest on its seat.

The preferred construction of the unit, comprising the check 10, the housing 11, and the cage 12, should be of such size that the same assembly can be used in pens of various sizes.

The cage 12 is held raised by friction in the housing 11 and so readily allows the passage of air into the barrel when the filling piston 2 is thrust down. The air that may be in the ink chamber, together with any remaining ink or sediment, is thus forced out of the barrel prior to the actual filling operation.

In thrusting the filling cap or piston 2 down to its full extent, the check valve cage 12, and the enclosed valve are carried down also until the valve seats (Figure 2); then with the pen, which is now empty and resting in the ink supply to the lines 1-1 or 2-2, according to the construction of the nib and feed plug, the cap or piston 2 is now drawn up, and entirely off the barrel. This will draw ink into the barrel, the valve 10 rises at the same time and so allows the air from the barrel to escape, and simultaneously ink will be drawn into the pen barrel itself.

The instant the piston 2 is off the end of the barrel, the check valve 10 will drop to its seat 9 by action of gravity, and will be held there by the atmospheric pressure, thus trapping the ink in the barrel. The rear cap 6 is then replaced, closing the end of the barrel, and at the same time the post 21 locks the valve on its seat.

The cap 6 is internally threaded to engage the threads 20 on the extended end of the cage housing 11, and is so formed as to cover and protect the bevel 14 on the end of the barrel. This cap 6 may support the cap 2 during the writing operation, as shown in broken lines at 2^x in Figure 1.

The cap 6 is fitted with an internal post 21, on approximately its center line, which post passes through the hole in the button-like head 19, and the hole in the upper end of the cage, and rests on the ball check 10, thus forcing the valve closed and firmly holding the same on its seat 9. The cap or piston 2 is of such length, between the closed end 22 and the packing 23, as to give a stroke which will create a displacement equal to the correct capacity of the ink barrel, so that the ink chamber can be filled as far as required by one operator stroke.

The open end of the filling cap or piston 2 has a counterbore 24 up to a series of fine threads 25, which may be left hand, and which terminate farther on in a recess, the upper end of which is shown as a beveled shoulder 26. This

open end of the cap 2 is fitted with a collar 27, of metal, having at its upper end threads to engage the threads 25 of the cap 2 with a tight fit, terminating in a bevel face 28, which, together with the shoulder 26, forms a recess in which is secured the packing 23. The other end of the collar 27 is fitted with internal threads 29, of the usual type, to engage the threads on the lower end of the pen barrel 1, in a comparatively easy fit, when the pen is closed. These threads are of such diameter as to clear the barrel 1 when the cap 2 is used as a piston during the filling operation. They start from a slight counterbore extending inward the proper distance to a shoulder. They are interrupted by two slots 30

(Figure 4), which extend a small distance past the shoulder of the threads 29 to or near to the fine threads 25. These slots 30 are used as a convenient means by which to insert the collar 27 in assembling the pen, and also act as vents for air in the piston.

The packing 23 is preferably a continuous ring punched or otherwise formed of any approved material. In assembling the pen it is inserted in the cap 2 ahead of the collar 27. The insertion of the collar 27 thus secures the packing 23 in place, and the pressure of the beveled end 28 forces the material of the packing 23 to bulge slightly, as shown best in Figure 1, so that when the cap is used as a piston on the barrel during the filling operation it makes an air-tight joint with the barrel, taking up any small variations in the diameters or surfaces of the parts.

This packing, as can readily be seen from the drawings, is placed where it cannot be contacted for any purpose except that for which it is intended. This provides cleanliness and keeps the packing in good condition for long and efficient service.

As shown in Figure 1 by the dot and dash lines 23, this filling cap 2 is shown in the writing position. The packing 23 preferably does not contact the rear cap 6. There are no openings in the cap 2 between the packing 23 and the closed end 22.

The cap 2 should give a volume displacement somewhat less than the total volume of the ink chamber, and this difference should be about equal to the volume needed for the air space 31, above the ink. Such an air space, as is well known, is necessary for proper performance during writing operation.

The pen is shown with the usual pocket clip 32, secured to the pen or its cap 2 in any satisfactory manner.

The surface 22, at the closed end of the cap 2, limits the displacement stroke of the piston. When the button-like head 19 has been lifted as a preliminary step, the lowering of the piston causes the top 22 to contact with the valve cage and the cage is thereby carried down to the position shown in Fig. 2. Thus the valve cage is depressed, but the valve is not on its seat, and the air in the piston passes around the valve into the pen barrel.

Sufficient clearance should be allowed at the closed end of the cap 2 so that it clears the extended threaded portion 20 of the housing 11.

The cap 2 serves not only as a cover for the pen, and as a piston for filling the pen, but it serves also as a measuring device for determining the amount of ink to be introduced into the barrel by any filling operation. The piston contains normally a definite volume of air. When the piston is forced on to the barrel, this air is

forced through the valve, which is now open, and into the barrel, thereby forcing out of the barrel an equal volume of the contents thereof; namely, ink, if any, and sediment and air. This volume is fixed and definite. When the piston is withdrawn, or a "draw" of ink takes place, an amount or volume of air is withdrawn from the barrel exactly equal to that forced in when the piston was thrust down, and of course an equal volume of ink enters the barrel from the ink supply. As stated above, the volume of the piston is somewhat less than the total volume of the pen barrel, so that a certain small volume of air 31 is always found in the barrel after every operation of filling.

Ordinarily, the piston is used but once for each filling operation. It is simply depressed as far as it will go, and then withdrawn and entirely removed. If it should be operated a second time, it would merely result in again displacing from the barrel a volume of ink equal to the volume of the piston, and the withdrawal of the piston will again cause the return to the barrel of an amount of ink equal to that displaced. Therefore, repetition of the filling process will merely refill the barrel. No matter how often this operation is repeated, the result will always be the same. But, as stated before, this is not the intended operation.

In Figure 1, 2^y shows in dotted lines the position of the piston as it moves down to expel the air and remaining ink from the pen barrel.

Referring to Figure 5, the rear end of the barrel 1^a, the cage housing 11^a and the button-like head 19^a are the same as similar parts in Figs. 1 to 4, inclusive. But the other parts are changed somewhat, but only in the following respects: The rear cap 6^a has the post 21^a shortened to meet a stem 33 of the ball faced valve 10^a of hard rubber, gutta-percha or plastic material, which engages the seat 9^a. Around the stem 33 is a very light spring 34 of bronze or other suitable wire, which fits the stem 33 next to the valve and is increased in diameter to seat on the shoulder 17^a in the cage 12^a. This spring 34 should have just sufficient tension to carry the weight of the ball faced valve 10^a, and the full head of the ink, if the pen were to be turned with this end down before the rear cap 6^a has been replaced.

The operation of this pen in this form is the same as the form first described, and so it need not be further described. The ball check 10 or the ball faced valve 10^a would perform equally satisfactorily without any spring.

Second form, Figs. 6 to 9, inclusive

Referring to Figures 6, 7, 8 and 9, a pen is shown having the general principles as the form first described, but differing somewhat from the first construction, particularly in the cap or piston 2.

The barrel 1 here is a straight cylinder from the bevel 14 for a length sufficient to accommodate the required stroke of the cap or piston 2, but from this point it may be either straight or tapered to the threads on the barrel. In this arrangement, what was in the form first described as the filling cap 2, as well as the cap to cover the pen point, has been divided into two parts, one the filling cap 2 proper, and the other the special collar 35, which is to remain on the barrel 1 when the cap 2 is removed to serve as a piston to fill the pen.

The filling cap 2 is fitted as before with the

packing 23 in a gland formed by the collar 27 head by the threads 25. The metal collar 27, in this arrangement, is provided with latches to engage with the part 35. Latches 36 on the cap 2 are made to removably engage with collar 35. Latches 36 enter the collar 35 and engage catches 37 in a metal catch collar 38, shrunk on the internally threaded collar 35. Just ahead of the threads 25 is a small section of small corrugations 39 parallel to the center line of the cap. A metal lock ring 40 (Fig. 6) is formed to engage these corrugations, and is also fitted with three recesses 41 to engage the sides of the latches 36 and thus keep the collar 35 in proper position. These recesses 41 should have the proper clearance for easy and proper operation.

The catch collar 38 is fitted with holes or catches 37 properly formed to fit the latches 36, and also allow their easy entrance and withdrawal. To this end the collar 38 is beveled at 42 to allow easy access of the latches on assembling the two parts. The parts are so fitted that the latches 36 engage the catches 37 and the parts are easily engaged by simply slipping the latches 36 into engagement with the catches 37, and may be separated by pulling them straight apart. An external band 43, formed with a recess to receive the extreme end of the cap 2, and to allow for small variations in the size of the parts, is found to be useful. The collar 35, in wake of the collar 38, is fitted with three recesses 44 (Fig. 9) in line with the catches 37, which act as keyways for the sides of the latches 36, as well as give the necessary spaces 44 for their operation on assembling. The portion of the collar 35 in wake of the collar 38 stops at the bevel 42, from which point it is extended slightly, at a reduced diameter, to act as a guide for the latches 36 on assembling.

The cap 2 is fitted with two vent holes at 45, by which to admit air as the piston 2 is separated from the head 35.

The rear cap 6 is the same as in the arrangement shown in Figs. 1, 2 and 3, except that its exterior is formed to meet, and hold the combined cap 2 and collar 35 in the writing position of the pen.

This arrangement allows the reduction of the diameter of the external threads on the end of the barrel 1 by any amount desired, subject to the size of the nib and feed plug, which allows the tapering of the barrel 1 towards the writing end. Further, the collar 35 forms a good finger hold, by which to hold the barrel during the filling operation.

Figs. 10 and 11

Referring to Figures 10 and 11, there is shown a modified form of separable piston and collar. The cap or piston, here marked 2^b, has the same internal threads 25^b beyond which is the packing collar 23^b, against which is screwed a compression collar 46. The lower end of the part 2^b, threaded portion 47, is shown interrupted, with three blank segments 48 (Fig. 11), and three threaded segments 47. These threads are separated by a blank area 49 of sufficient length to allow free access to the collar 47 during assembling. These threads should both preferably be left-hand in this arrangement, although if the thickness of the material will allow, the threads 47 may be made of a diameter such as to allow the assembling of the collar 46 without the interruption of the threads. If this is done the threads 47 should still be left-hand while the threads 25^b

may be right-hand. The collar 35^b has external threads to engage the threads 47, which would also be interrupted to allow easy assembling of the parts, thus necessitating only a part of a turn to assemble the collar 35^b. This collar is also threaded internally, in the usual manner, to engage the external threads on the end of the pen barrel 1. The packing collar 47 is externally threaded to engage the threads 25^b, but these external threads are interrupted to pass the threads 47 in the end of the cap 2^b. When it is by these interrupted threads, and is in the area 49, it may be readily assembled, the packing 23^b, having previously been placed, by the proper tool made to fit the three recesses 50 in the collar 35^b for this purpose.

Third form, Figs. 12 to 15, inclusive

Referring to Figs. 12, 13, 14 and 15, there is shown a structure, further modified as to the piston and as to the check valve, but still retains the general principles of the invention.

In this form, the barrel 1 is shown of the usual size at the end which carries the pen, but the rear end is reduced in diameter, the larger and smaller sections being connected by a tapered portion 51. The pen cap or piston 2 is to function also as a filling piston, as in the other forms, in one position (Fig. 12) as a protector for the pen, and in the other, as a filling piston (Fig. 13). The smaller section of the barrel is of sufficient size to function with the piston as a filling element, as in the other forms. As an additional element, the post, which in the earlier figures is shown as being the closing cap and valve seating device 6, is here shown with the same body 6, but with a long sleeve or skirt 53 attached thereto, and reaching to the tapered part 51 of the barrel. This element is of approximately the same external size as is the large part 1 of the pen barrel, and when in place meets the taper 51, thus making the barrel of the same size throughout its length. This cap 6 is provided with internal threads which engage with the external threads of the housing 11, just as do the internal threads of the cap 6 of Fig. 1, so that as the cap, with its attached skirt 53, is secured in place, the check valve will be seated, and the sleeves or skirt 53 will move to register with the bevel 51 on barrel.

In this form, the barrel is first emptied and then filled by the piston 2, just as in the first form. The closure 6 and its attached skirt or sleeve 53 is removed during this operation.

In this form the packing for the piston is different from the other forms. The packing ring 56 is of metal, and is beveled at its sides at 57 to allow easy access of the filling cap 2, during the filling operation, and is also fitted, on its other face, with two recesses 57 (Fig. 15) for a spanner wrench or the like to actuate the ring 56.

The housing 11, of any suitable material, in the end of the barrel, is fitted with an inside hole, part of which is conical and made to fit a similar portion 58 on the ball faced checked valve 10, with the portion of the hole below the conical portion of sufficient diameter to allow an area such as will let the air by-pass the lower end of the valve 10. The portion above the conical portion is smaller than the diameter of the hole, so as to admit the stem or post 59, which in this case is integral with the ball faced valve. This outer portion of the hole is further fitted with three grooves 60 which allow the air to readily by-pass the stem 59 and valve.

The ball faced check valve 10 is fitted with a conical section 58, just behind the half-spherical section, which terminates in the stem 59, which is of sufficient length when seated to be a small distance above the outer end of the bearing 11, and which continues to a slightly reduced diameter having a taper to receive the small button-like metal head 19. In this arrangement, the head 19 is shrunk on after the valve is assembled, but it may be secured in any other approved manner. The head 19 and the stem 59 are rounded at the outer end to properly contact the rear cap 6 when the pen is closed, and the closed end 22 of the cap 2 in the filling operation.

The rear cap 6 of plastic material, without any post, is fitted with internal threads to engage the threads of the portion 20 of the housing 11 and also with a cylindrical sleeve 53 of plastic material, integral therewith. This sleeve 53 has an inside diameter sufficient to clear the packing 23 and an outside diameter giving the required strength, but preferably somewhat smaller than the outside diameter of the cap 2.

This sleeve 53 forming part of the rear cap 6 terminates at its outer end in a conical portion to easily fit the section 51 on the barrel 1. The conical portion on the barrel 1 with the sleeve 53, should be of such length, and so designed that a movement along the barrel of about $\frac{1}{8}$ inch is possible. This will always insure the proper seating of the check valve 10. For easy manufacture of the rear cap 6 it is fitted with a plug 61 at the rear end which is cemented in place, but may be secured in any approved manner; or it may be made integral with the rest of the cap.

The cap 2 is of the usual type and appearance, with the inside diameter slightly larger than the diameter of the rear, smaller end portion of the barrel 1, and is of a length to give the required stroke for the proper air displacement. The open end is fitted with the usual counterbores 24, and the internal threads 29 to engage the threads on pen end of the barrel 1. Just above the threads 29 in a small slightly beveled portion, to further aid in the starting of the cap 2 over the end of the barrel and packing 23, holes 45 are formed in the cap to vent the same in the closed position. The inside of the top 22 of the piston 2 contacts and returns the valve and its stem to thrust down, the same as an incident to the filling operation.

This arrangement gives a slightly increased displacement of air during the filling operation, due to the location of the packing, and gives a valve and filling cap arrangement of simple form. The larger rear cap is less likely to be dropped, and if dropped its loss less likely, and its recovery much easier. This larger style of rear cap may also be incorporated in the design of the pen shown in Figure 1 where it would have the effect of protecting the surface of the barrel contacted by the packing in the filling cap 2.

It is not the intention to limit the arrangement of the packing 23 or the packing gland collar 27 to the foregoing designs.

Operation

In the filling operation, the rear cap 6 is first removed, exposing the button-like head 19. With the pen point (nib) in or over the ink supply (bottle) the head 19 is lifted until it stops. The filling cap 2 is then placed on the rear end of the barrel 1 and pushed down. It will start easily over the beveled end 14. The filling cap is then

forced down as far as is possible, the body of the barrel being grasped at any place. There are no openings to cover. This movement of the piston will thrust out the air, and any ink or sediment that may be in the barrel, and also will return the valve cage 12, or the entire valve in Figs. 12, 13 and 14, to its original position. The filling cap 2 is shown in its lowest position, shown at 27.

With the pen now in the ink supply, the filling cap 2 is drawn off of the barrel, thus drawing ink into the barrel. The rear cap 6 is now replaced and the pen is ready for use.

Attention is directed to the fact that the arrangements are exceedingly simple, that the constructions are flexible, but positive in action, and yet require no excessive refinements of construction. It provides the necessary air space above the maximum ink supply, yet the pen will carry a large volume of ink, four to five cubic centimeters, when my feed arrangement, Patent No. 2,136,371 is used for the largest sizes of pens now in general use. It has no rubber sack or sleeve, and there is a visible ink supply the entire length of the barrel. This pen does not depart in general appearance from the conventional; it is easily adapted to streamlining (so-called), as well as for desk use. The filling cap can be grasped in any manner; there is no hole to cover with the finger or thumb; and the parts are comparatively few, simple and lasting.

From the foregoing descriptions, taken in connection with the accompanying drawings, it is thought the construction, operation and advantages of the invention will be apparent.

Having described the principle of my invention, what I claim is:

1. A self-filling fountain pen, comprising an ink barrel having a pen point and feeding plug at one end and an opening through the other end, a piston operable externally of the barrel and over the opening in the end thereof, packing within the piston adapted to cooperate with the outside of the pen barrel for maintaining a close fit between the barrel and the piston, and a valve structure without the opening in the end of the barrel and cooperating with the piston to control the opening.

2. A self-filling fountain pen, comprising an ink barrel having a pen and feed plug at one end and an opening for the passage of air into and out of the barrel at the other end, an imperforate piston operable externally of the barrel and over the air opening therein, a check-valve on the outside of the barrel normally controlling the air opening, manually operable means for moving the check-valve out of operative relation with the opening it controls, so that air can pass therethrough when the piston is moved to introduce air into the barrel, and means operated by the piston for restoring the valve to its normal position.

3. A self-filling fountain pen, comprising an ink barrel having a pen and feed plug therefor at one end and an opening for the passage of air into and out of the barrel at the other end, a piston operable externally of the barrel and over the air opening therein, a check valve normally controlling the admission of air through the air opening, means for moving the check valve out of operative relation to the air opening so that air can pass therethrough as the piston is depressed, and means actuated by the piston as it nears the end

of its inward stroke for restoring the valve to its normal position.

4. A fountain pen, comprising an ink barrel having a pen feed opening at one end and a valve controlled opening at the other, a piston operable externally of the barrel for introducing air into the barrel, a check valve normally preventing the passage of air into the barrel, manually operated means for moving the valve out of its normal position and into the path of movement of the piston as it makes its stroke in one direction, so that the piston will restore the valve to its normal position near the end of its stroke, and means for closing the end of the barrel and locking the valve on its seat in normal position.

5. A fountain pen, including an ink barrel having a pen feed opening at one end and a valve controlled opening at the other, a piston operable externally of the barrel for forcing air through the valve controlled opening and into the barrel, a check valve for preventing the movement of air through the opening in one direction, a cage for the check valve, manually operated means for moving the check valve and its cage out of normal position, and means operated by the piston on its inward stroke to move the valve back to its normal position.

6. A self-filling fountain pen, including a pen barrel having a feeding opening at one end and a valve controlled opening at the other, a hollow piston operable externally of the barrel and over the valve controlled opening, adapted to force air contained in the piston through the opening into the barrel, a check valve normally preventing the passage of air into the barrel but permitting air in the barrel to pass from the same, means for manually moving the check valve from operative to inoperative position, a valve cage having an elongated chamber within the same in which the valve rests and may move to a limited extent from and toward the valve seat, a housing in which the cage and its enclosed valve may be moved manually, and means to restore the valve to its normal position after it shall have been moved therefrom.

7. A self-filling fountain pen, comprising an ink barrel having a pen point and feeding plug at one end and an opening through the other, an imperforate piston operable externally of the barrel and over the opening in the end thereof, packing within the piston for cooperating with the outside of the barrel to effect a close fit between the piston and the barrel, and a valve structure cooperating with the opening in the end of the barrel to control the same, which valve mechanism includes a ball valve, a valve cage having a space therein for the valve to rest easily over the opening and to move longitudinally in the cage to a limited extent, and a housing within which the cage and its supported valve may be moved.

8. A self-filling fountain pen, comprising an ink barrel having a pen point and feeding plug at one end and an opening therein at the other end with a valve seat around the same on the outside of the barrel, an imperforate cap for the pen and ink feeding plug which also serves as a filling piston adapted to operate externally of the barrel at the end opposite the pen, a packing within the cap and piston which cooperates with the outside of the barrel to effect a close operating fit between the piston and the barrel, and a

valve structure including a valve and a manually movable cage therefor without the opening in the end of the barrel and cooperating with the valve seat to control the passage of air through the opening, the valve cage being in the path of the piston near the end of its down stroke, whereby the valve and its cage are forced into operative position with respect to the valve seat.

9. A self-filling fountain pen, comprising an ink barrel having a pen point and a feeding plug at one end and an opening in the other, a pen cap and filling piston, a packing in the piston adapted to cooperate with the outside of the barrel to effect a close fit between the piston and the barrel, a valve structure carried by the barrel and operating to close the opening in the barrel when required, and a barrel cap for closing the end of the barrel when the piston is not on the barrel and for forcing the valve to its seat.

10. A self-filling fountain pen, comprising an ink barrel having a pen point and feeding plug at one end and an air opening in the other, a pen cap and filling piston, a packing in the piston to effect a close fit between the piston and the barrel, a valve structure carried by the barrel and operating to control the air opening in the barrel, and a barrel cap adapted to close the end of the barrel and simultaneously force the valve to close the air opening in the barrel.

11. A self-filling fountain pen, comprising an ink barrel having a pen point and feeding plug at one end and an air opening in the other, a pen cap and filling piston, a packing in the piston to effect a close fit between the piston and outside of the barrel, a valve structure mounted on the barrel and operating to control the air opening, and a barrel closing cap having a post thereon at approximately the center part thereof whereby to cover the end of the barrel and simultaneously seat the valve over the air opening so as to close the valve and hold the valve to its seat.

12. A fountain pen comprising an ink barrel having a pen feed opening at one end and a valve controlled opening at the other, a piston operable externally of the barrel for introducing air into the barrel, a check valve having an elongated stem by which the valve may be manually moved from operative relation with respect to its seat and by which the valve stem may be moved into the path of the piston as the latter makes its stroke in one direction, so that the piston will restore the valve to its normal position near the end of its stroke.

13. A fountain pen comprising, an ink barrel having a pen feed opening at one end and a valve controlled opening at the other; a piston operable externally of the barrel for introducing air into the barrel; a check valve having an elongated stem by which the valve may be manually moved from operative relation to its seat; a valve housing having an elongated recess therein for part of its length for the valve to move in and an open-through the remainder of the housing through which the valve stem may move into the path of the piston as the latter makes its stroke in one direction, so that the piston will restore the valve to its normal position near the end of its down stroke.
